ABSTRACT OF THE DISCLOSURE

Rare earth perfluorotertiarybutoxides containing coor-
dinated ammonia and having the formula

wherein M represents an ion of a rare earth metal, are
prepared by reacting prefluorotertiarybutanol with an
ionizable rare earth salt and ammonia in the presence
of an inert solvent. These compounds are novel and more
volatile than any rare earth compounds previously known.
Because of their volatility, the compounds are useful in
such applications as the separation of individual rare
earths by fractional sublimation.

BACKGROUND OF THE INVENTION

This invention relates to rare earth perfluorotertiary-
butoxides containing coordinated ammonia and to a
method for their preparation.

Efforts have been made in recent years by independent
teams of researchers to develop volatile compounds of
rare earth metals. One potential application of these com-
pounds would be in processes for separating the individual
rare earth elements. Because the rare earths are very
similar chemically, especially with respect to their salts,
which tend to form mixed crystals and solid solutions,
they are very difficult to separate. A typical present com-
mercial method uses solutions of expensive reagents to
elute the rare earths from ion exchange columns. In addi-
tion to being costly, this method is also quite slow.

The vapor-phase separation of rare earths by fractional
sublimation and gas chromatography has been accom-
plished using rare earth tris chelates of β -diketones, such
as 2,2,6,6-tetramethyl - 3,5 - heptanedione. These chelates
were the most volatile rare earth compounds known prior
to our invention. For example, the ytterbium tris chelate
of 2,2,6,6 - tetramethyl - 3,5 - heptanedione sublimes at a
moderate rate at a pressure of about 0.08 mm. Hg and
at a temperature of 115 to 120° C.

The novel compounds of this invention are rare earth
perfluorotertiarybutoxides. Rare earth hydrocarbon alk-
oxides are known compounds; however, they are either
nonvolatile or they volatilize with great difficulty. For
example, the most volatile of these compounds, the iso-
propoxides and tertiarybutoxides, require temperatures of
200 to 300° C. and pressures of 0.1 to 0.0001 mm. Hg
in order for sublimation to occur.

It is an object of this invention to provide novel, highly
volatile compounds of the rare earth elements.

SUMMARY OF THE INVENTION

This invention provides novel rare earth compounds
which are more volatile than any rare earth compounds
previously known. These novel compounds are rare earth
perfluorotertiarybutoxides containing coordinated ammonia,
and having the formula $(NH_3)_3M[OC(CF_3)_3]_3$,
wherein M represents an ion of a rare earth metal. As
used herein and in the appended claims, the term "rare
earth" refers to the elements scandium, yttrium, and the
elements having atomic numbers 57 through 71 inclusive.

The compounds of this invention are prepared by react-
ing, under substantially anhydrous conditions, perfluorot-
ertiarybutanol with an ionizable rare earth salt and am-
monia in the presence of an inert solvent, as represented
5 by the following equation:

wherein M represents an ion of a rare earth metal and X
10 represents an anion forming an ionizable salt with the
rare earth metal. This result is entirely unexpected in
view of the prior art. It is known that when ionizable
salts of other metals react with an alcohol in the presence
15 of excess ammonia to produce metal alkoxides, the metal
alkoxides obtained are free of coordinated ammonia. At
least two attempts to prepare rare earth hydrocarbon
alkoxides by this method have been reported, and these
attempts were both unsuccessful. See K. S. Mazdiyasi
20 et al., The Preparation and Some Properties of Yttrium,
Dysprosium, and Ytterbium Alkoxides, in Inorganic
Chemistry, 5, pp. 342-346 (1966), and D. C. Bradley,
Preparative Inorganic Reactions, vol. 2, ed. by W. L.
Jolly, Interscience-Wiley, New York, 1965, pp. 174-177.
25 The latter reference, at page 175, indicates that a stable,
insoluble ammoniate is obtained instead of the alkoxide.
Prior to our invention, such ammoniates were the only
compounds of the rare earth elements known to contain
coordinated ammonia; and, unlike the compounds of this
invention, these ammoniates are wholly inorganic.

30 The process of this invention is conveniently carried
out at room temperature and atmospheric pressure. At
these conditions the ammonia is present as a gas and forms
an atmosphere over the remainder of the reaction mixture.
35 The reaction proceeds readily at these conditions, but tem-
peratures departing from room temperature and pressures
departing from atmospheric pressure can be used if de-
sired. The upper temperature limit is determined by the
40 thermal stability of the reactants and products, and is
about 250° C. The lower temperature limit is that at
which the reaction rate becomes impractically slow, and
is about -80° C. The upper pressure limit is determined
simply by the strength of the reaction vessel employed.
45 Pressures below atmospheric can be employed provided at
least a stoichiometric amount of ammonia is present.

It is preferable to use at least a stoichiometric amount,
based on the rare earth salt, of perfluorotertiarybutanol
in the reaction in order to avoid product containing the
50 anion of the salt. It is also preferable to use at least a
stoichiometric amount of ammonia in order to drive the
reaction toward completion. Generally, it is preferable to
use an excess of both of these reactants.

55 The halides and sulfates of the rare earth metals are
representative of the ionizable rare earth salts which can
be used in the process of this invention. The trichlorides
are preferred. Particularly good results are obtained using
the trichlorides of yttrium and the elements of the
lanthanum series, i.e., the elements having atomic num-
bers 57 through 71.

60 Most common organic solvents are suitable as the
inert solvent employed in the reaction, including benzene,
chloroform, cyclohexane, ligroin, tetrahydrofuran, acet-
nitrile, ether and methylenedichloride.

Because of their high volatility, the compounds of this
65 invention are useful in many applications. As previously
indicated herein, one application of these compounds
is in processes for separating the individual rare earth
elements. Separation can be effected by either fractional
70 sublimation or gas chromatography in accordance with
methods known in the art. For example, separation by
fractional sublimation is achieved by introducing mixtures
of the compounds of this invention into a vacuum sub-

limitor, such as developed by Berg and Hartlage and described in *Anal. Chim. Acta*, 33, pp. 175-181 (1965). The volatilized compounds are moved through the sublimator with an inert gas, such as nitrogen or helium, as carrier. Contact of the vapor with the walls of the sublimator results in selective condensation of the compounds. The thermal gradient in the sublimator preferably ranges from about 130° C. in the hottest zone to about 15° C. at the coldest end. Separation by gas chromatography is achieved by introducing mixtures of the compounds into a column having, typically, an inside diameter of 2 to 4 mm. and a length of 10 to 100 cm., and constructed of an inert, nonmetallic material, such as glass or polytetrafluoroethylene. The column is packed with a convenial solid support, such as diatomaceous earth, and a liquid phase such as a silicone polymer (e.g., General Electric Co. SE-30) or a hydrocarbon (e.g., Apiezon grease L, M, N, or T). The column and inlet port temperatures are preferably in the range of 100 to 200° C., and the separation is effected in the substantial absence of moisture and oxygen.

When subjected to controlled hydrolysis, the components of this invention produce extremely pure and reactive powders of rare earth oxides.

Other potential applications of the compounds of this invention include their use as catalysts in homogeneous gas phase reactions, and as the lasing component in gaseous lasers.

The following examples further illustrate the invention. In each of the examples, the product was identified by elemental and infrared spectrum analyses.

EXAMPLE 1

The entire preparation was performed under substantially anhydrous conditions. Into a 3 neck, 100 ml., round bottom distilling flask were placed 3.91 grams of anhydrous ytterbium trichloride. Using vacuum techniques, 50 ml. of diethyl ether and 10.0 grams of perfluorotertiarybutanol were condensed into the flask at -80° C. The contents of the flask were warmed to room temperature and then stirred as gaseous ammonia was slowly added until the pressure in the flask remained constant at one atmosphere. White solids (NH₄Cl) formed during the addition of ammonia. After the solids had settled, the clear mother liquor was decanted. Ether was evaporated from the liquor under vacuum, leaving the crude product as white solids. The crude product was purified by being sublimed twice at 0.1 mm. Hg and 85° C. The purified product was identified as (NH₃)₃Yb[OC(CF₃)₃]₃.

EXAMPLE 2

The procedure of Example 1 was followed except the reactants were 6.93 grams of anhydrous lanthanum trichloride and 20.0 grams of perfluorotertiarybutanol, and the solvent consisted of 100 ml. of methylenedichloride. The product was identified as (NH₃)₃La[OC(CF₃)₃]₃.

EXAMPLE 3

The procedure of Example 1 was followed except the materials used were 3.72 grams of gadolinium trichloride, 10.0 grams of perfluorotertiarybutanol, and 100 ml. of diethyl ether, and the product was sublimed twice at 100° C. The product was identified as

EXAMPLE 4

The procedure of Example 1 was followed, except the materials used were 2.76 grams of yttrium trichloride, 10.0 grams of perfluorotertiarybutanol, and 100 ml. of diethyl ether, and the reaction product was sublimed twice at 105° C. The product was identified as

EXAMPLE 5

A comparison of the relative volatilities of the compounds of the present invention with the rare-earth complexes of 2,2,6,6-tetramethyl-3,5-heptanedione (previously regarded as the most volatile rare-earth compounds) was made by determining the temperature required to give similar rates of sublimation of comparable complexes. A sublimator containing Yb[OC(CF₃)₃]₃(NH₃)₃ and another containing the tris-2,2,6,6-tetramethyl-3,5-heptanedione chelate of ytterbium [Yb(thd)₃] were attached to the same vacuum line and the compounds were sublimed simultaneously. The minimum temperature required for a perceptible rate of sublimation was 75 to 80° C. for Yb[OC(CF₃)₃]₃(NH₃)₃ and 115 to 120° C. for Yb(thd)₃. The lower required temperature demonstrates the greater volatility of the compounds of this invention.

We claim:

1. Rare earth perfluorotertiarybutoxides containing coordinated ammonia and having the formula

wherein M represents an ion of a rare earth metal.

2. The rare earth perfluorotertiarybutoxides of claim 1 wherein the rare earth metal is selected from the group consisting of yttrium and the elements having atomic numbers 57 through 71 inclusive.

3. The rare earth perfluorotertiarybutoxides of claim 1 wherein the rare earth metal is selected from the group consisting of yttrium, lanthanum, gadolinium and ytterbium.

4. A process for preparing rare earth perfluorotertiarybutoxides containing coordinated ammonia and having the formula (NH₃)₃M[OC(CF₃)₃]₃ wherein M represents an ion of a rare earth metal, which process comprises reacting, under substantially anhydrous conditions, perfluorotertiarybutanol with an ionizable rare earth salt and ammonia in the presence of an inert solvent.

5. The process of claim 4 wherein the amount of ammonia employed is in excess of the stoichiometric amount required based on the rare earth salt.

6. The process of claim 5 wherein the amount of perfluorotertiarybutanol employed is in excess of the stoichiometric amount required based on the rare earth salt.

7. The process of claim 6 wherein the ionizable rare earth salt is a trichloride of a rare earth metal.

8. The process of claim 7 wherein the rare earth metal is selected from the group consisting of yttrium and the elements having atomic numbers 57 through 71 inclusive.

9. The process of claim 8 wherein the rare earth metal is selected from the group consisting of yttrium, lanthanum, gadolinium and ytterbium.

10. The process of claim 9 wherein the ammonia is present as a gas and forms an atmosphere over the remainder of the reaction mixture.
